UNITED STATES PATENT OFFICE.

GEORGE W. WILMOT, OF HAZLETON, PENNSYLVANIA, ASSIGNOR TO WILMOT ENGINEERING COMPANY, OF HAZLETON, PENNSYLVANIA, A CORPORATION OF PENNSYLVANIA.

COAL JIG.

Application filed December 23, 1921. Serial No. 524,343.

To all whom it may concern:

Be it known that I, GEORGE W. WILMOT, a citizen of the United States, and a resident of Hazleton, in the county of Luzerne and 5 State of Pennsylvania, have invented an Improvement in Coal Jigs, of which the following is a specification.

My invention relates to apparatus which is adapted for use in the washing of coal, or 10 ores of various kinds, although designed by me primarily for use in a coal jig for washing coal.

In the use of a jig of the vibrating pan type of the character depicted in the drawings, it is desired that, as far as may be practicable, a constantly forwardly moving flow of the water in the tank shall be maintained through the jig pan. Therefore, it is one 15 of the objects of my invention to provide a new and novel improved means to prevent reverse movement or flow of the water within the pan as the latter is moved upwardly in its vibratory movements. By this means the occurrence of conditions in the water in 20 the jig pan at intervals under which the coal may settle or tend to settle to the bottom thereof with the slate and other relatively heavy impurities which it is desired to remove is prevented.

30 More specifically my invention relates to the construction of valve mechanism underneath the jig pan by which the upward forward flow of the water through the pan is more efficiently controlled than heretofore 35 has been the case.

A further object is to provide a structure which is both simple and durable and which may be economically manufactured.

To these and other ends my invention 40 comprehends the construction and arrangement of parts as hereinafter more fully described and particularly pointed out in the claims.

In order that the invention may be more 45 readily understood and the practical advantages thereof fully appreciated, reference should be had to the accompanying drawing in which one form of embodiment of the same is shown. However, it will be understood 50 that changes in the details of construction may be made within the scope of the claims without departing from the invention.

In the drawings:

55 Fig. 1 is a view in longitudinal vertical

section of a coal and ore washing apparatus embodying my invention;

Fig. 2 is an enlarged longitudinal vertical sectional view of the jig pan shown in Fig. 1;

Fig. 3 is a sectional view of a portion of the bottom of the jig pan and of the valve mechanism showing more clearly details of construction and indicating the operation thereof;

Fig. 4 is a top plan view of the jig pan with the greater portion of the bottom removed therefrom;

Fig. 5 is a transverse sectional view of the jig pan;

Fig. 6 is a top plan view of a section or portion of the valve mechanism; and

Fig. 7 is a longitudinal sectional view of a hollow pipe with closed ends which is adapted to be employed as a valve.

Referring to the drawings: 1 designates a portion of the tank of the coal and ore washing apparatus, and 2 one of the parts of the frame structure which supports the said tank.

3 designates the opposite side walls of the jig pan which walls are provided at their lower edges with laterally and outwardly turned flanges 4. The jig pan is supported upon depending links or bars 5, the lower ends of which are guided in openings through brackets 5^a. The said links or bars are supported at their upper ends in the usual manner upon eccentrics one of which is shown at 6 in Fig. 1 upon a shaft 7 which is 85 adapted to be rotatably driven through a power belt 8 and a wheel or pulley 9.

The gate at 15 at the forward end of the bottom of the jig pan 3 is hingedly connected and supported at 16 at its inner end 95 and is supported at its outer end by means of links 17 in the usual manner. The upper ends of these links are connected to the outer or forward ends of bars 18 pivoted at 20 upon uprights or posts 21. The 100 opposite ends of the said bars 18 are provided with adjustable weights 22.

The bottom 25 of the jig pan is provided with the usual perforations 26, the size of the perforations depending upon the 105 size of the lumps of coal or other ore being washed.

The valve mechanism previously referred to is situated underneath the bottom of the jig pan and comprises a plurality of base 110

members 30, four being provided in the present construction. The portions of these members upon opposite sides of the center 31 thereof may be regarded or described 5 broadly as of pan-like formation. The said portions upon opposite sides of the central rib 31 are provided with side portions 32 which fit against the under side of the bottom 25, as indicated in Fig. 2 of the drawings. The opposite ends of the members 30 terminate in vertical walls 33. Laterally and outwardly extending flanges 34 are provided at the upper ends of the end walls 33 which flanges are situated underneath the 10 flanges 4. The opposite side edges of the bottom 25 extend beyond the planes of the side walls 3 of the jig pan and the end walls 33 of the base members 30 of the valve mechanism and are situated intermediate 15 the flanges 4 and 34. Screw bolts 35 extend through these flanges and through the opposite edge portions of the bottom so that all three of these parts are secured firmly together. The contact of the edges of the 20 side walls 32, the end walls 33 and of the central rib 31 with the under side of the bottom 25 forms a plurality of chambers underneath the said bottom. The bottoms of these respective chambers are provided 25 with longitudinally extending narrow openings 40 upon the opposite sides of which narrow flanges 41 are provided. The upper edges of these flanges 41 are provided at intervals with projections 42 which 30 terminate a short distance below the under side of the bottom 25 of the jig. These projections are of less thickness than the thickness of the flanges 41 so that shoulders 43 are provided between the said projections 35 and the adjacent inner edges of the said flanges. The inner adjacent and opposing edges of the flanges 41 constitute seats for the elongated valve members 46, which 40 valve members are of cylindrical form and 45 also are hollow. When these valve members are in their lowermost positions as shown in Figs. 2 and 3 of the drawings the elongated openings 40 are closed and the said valve members occupy this position 50 both when the jig is stationary and when it is being moved or lifted upwardly. The opposite ends of the valve members 46 are adapted to be closed by screw threaded plugs 47 although if preferred the said plugs 55 may be omitted so that the opposite ends of the said valve members will remain open. In actual practice, however, it is preferred to retain the plug closures so that a desired amount of water or some other substance 60 may be introduced into the said valves so as to vary their weight, as is indicated in Fig. 7. If it is desired that the valves shall respond quickly during the vibrations of the jig pan so as to quickly open and close 65 the passageways 40, the said valves should

be lighter than if it is desired or preferred to have them respond more slowly. In other words, if the tubular valve members 46 are weighted so that they are relatively very heavy they will not operate as quickly 70 to open and close the said passageways 40 as they would if they were lighter. It will be apparent, therefore, that by providing means whereby the weight of the tubular valve members may be varied I have provided means whereby the flow of water through the jig pan due to the vibratory motions thereof may be controlled to a greater or less extent. By this means the 75 efficiency in operation of the jig in the washing of coal or ore materials may be increased.

It will be understood that when the jig pan descends in the operation thereof the tubular valve members 46 are moved upwardly away from their seats upon the adjacent opposing corners or edges of the flanges 41 so as to open the passageways 40 and permit the upward flow of water there-through and that upon the upward movement of the said jig pan the said valve members move in the opposite direction to close the said passageways and thus prevent a backward or downward flow of water from the jig pan through the perforations 95 26. As a result of the presence of these valves the flow of water through the said jig pan is more continuous and more constant, in consequence of which the coal or ore is more efficiently and more completely 100 separated from impurities, such as slate, etc., than otherwise would be the case.

In the use of the apparatus, for instance for washing coal, the coal is discharged from a chute 50 into the rear end portion of 105 the jig pan between the rear wall thereof and a plate 51, the lower edge of which is situated a greater or less distance above the bottom 25 of the said jig pan. The vibratory movements of the jig pan are such as 110 to cause forward movement of the coal together with any slate or other impurities intermixed therewith. The slate and other impurities which are heavier than the coal travel along upon the bottom 25 of the jig 115 pan while the lighter material, coal, travels along within the water above the said slate and is ultimately discharged through the discharge chute 52. The slate piles up upon the bottom of the discharge gate 15 until 120 its weight is sufficient to overbalance the weights 22, whereupon the said gate is opened a sufficient distance to allow the slate to be discharged from the said gate. The operation will not be further described 125 because such operation is well known to those skilled in the art.

Having thus described my invention, what I claim and desire to secure by Letters Patent is:

1. In apparatus of the character described, the combination of a jig pan having a perforated bottom, a plurality of members secured to the said jig pan and situated underneath the said pan in contiguous relation to each other, said members respectively forming with the bottom of the said jig pan chambers and each of said members having openings through the bottom thereof, valves for controlling the passage of water through said openings, and means for guiding said valves in their movements and retaining them in operative relation with respect to said openings.
- 15 2. In apparatus of the character described, the combination of a jig pan having a perforated bottom, elongated pan-like members secured to said jig pan and situated underneath the said bottom and forming with the latter chambers, elongated openings in the bottoms of said members, said openings having upwardly extending flanges upon the opposite sides thereof, which flanges are provided with upwardly extending projections located at intervals, and an elongated valve member situated between the said projections and adapted to contact with the edges of the said flanges.
- 25 3. In apparatus of the character described, the combination of a jig pan having a perforated bottom and having laterally and outwardly extending flanges at the lower edges of its opposite sides, pan-like members extending across the said jig pan and situated underneath the said bottom and forming therewith chambers, the opposite ends of said members being provided with flanges, means for connecting the said flanges to the flanges upon the opposite sides of the said jig pan, and the said pan-like members being provided with openings in the bottoms thereof, said openings having flanges upon the opposite sides thereof, which flanges are provided with upwardly extending projections located at intervals, and valves situated above said openings between the said projections.
4. In apparatus of the character described, the combination of a jig pan having a perforated bottom, elongated pan-like members secured to the said jig pan and situated under the bottom thereof, the upper edges of the side and end walls of the said members contacting with the bottom of the said jig pan, and the said members each having a central partition wall dividing each of the same into two chambers, elongated openings through the bottoms of said respective chambers, projections situated at intervals upon the opposite sides of the said openings, and elongated tubular valves situated between the said projections and adapted to control the passage of water through the said openings.
5. In apparatus of the character described, the combination of a jig pan having a perforated bottom, means for vibrating the said jig pan to effect the passage of water through the same, a plurality of pan-like members secured to the said jig pan and situated underneath the said perforated bottom, the side and end walls of the said members co-operating with the said perforated bottom to form chambers underneath the latter, and the said members each being provided with narrow openings through the bottoms thereof, elongated valves situated over the said openings and adapted to control the flow of water therethrough, and means upon the opposite sides of each of said openings for retaining the said valve members in position and guiding the same in their movements with respect to the said openings.

In testimony that I claim the foregoing as my invention, I have hereunto signed my name this 17th day of Dec., A. D., 1921.

GEORGE W. WILMOT.
